(57) **CLAIM**

The ornamental design for protective case for an electronic tag, as shown and described.

DESCRIPTION

FIG. 1 is a front, right, and top perspective view of a protective case for an electronic tag, showing my design; FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged detailed view of encircled area 9 in FIG. 1.

The broken lines in the drawings depict portions of the article that form no part of the claimed design.
